[57] **CLAIM**

The ornamental design for an automobile seat tray, as shown and described.

DESCRIPTION

FIG. 1 is a top, right perspective view of an automobile seat tray in accordance with a first preferred embodiment of the present invention, showing an automobile seat in phantom lines;

FIG. 2 is a top plan view of the automobile seat tray of FIG. 1;

FIG. 3 is a bottom plan view of the automobile seat tray of FIG. 1;

FIG. 4 is a right elevational view of the automobile seat tray of FIG. 1;

FIG. 5 is a left elevational view of the automobile seat tray of FIG. 1;

FIG. 6 is a rear elevational view of the automobile seat tray of FIG. 1, the front elevational view being a mirror image thereof;

FIG. 7 is a top plan view of an automobile seat tray in accordance with a second preferred embodiment of the present invention, the right and left elevational views being identical to FIGS. 4 and 5, respectively;

FIG. 8 is a bottom plan view of the automobile seat tray of FIG. 7;

FIG. 9 is a rear elevational view of the automobile seat tray of FIG. 7, the front elevational view being a mirror image thereof;

FIG. 10 is a top plan view of an automobile seat tray in accordance with a third preferred embodiment of the present invention, the left and right elevational views being identical to FIGS. 4 and 5, respectively;

FIG. 11 is a bottom plan view of the automobile seat tray of FIG. 10; and,

FIG. 12 is a rear elevational view of the automobile seat tray of FIG. 10, the front elevational view being a mirror image thereof.

The broken line showing of environment is for illustrative purposes only and forms no part of the claimed design.
